INVENTOR

G. W. Williams,
BY *Henry V. Bright* ATT'Y

UNITED STATES PATENT OFFICE.

GEOFFREY WATKIN WILLIAMS, OF BURGESS HILL, ENGLAND.

PHONOGRAPH-RECORD CABINET.

1,389,610.

Specification of Letters Patent. Patented Sept. 6, 1921.

Application filed February 8, 1921. Serial No. 443,425.

To all whom it may concern:

Be it known that I, GEOFFREY WATKIN WILLIAMS, subject of the King of Great Britain, residing at "The Knoll," Burgess Hill, Sussex, England, have invented new and useful Improvements in Phonograph-Record Cabinets, (for which I have filed an application in Great Britain, Jan. 17, 1920, application No. 1,559;) and I do hereby declare the following to be a full, clear, and exact description of the invention, such as will enable others skilled in the art to which it appertains to make and use the same.

This invention relates to cabinets or the like for the storage of gramophone disk records of the kind which are divided into a plurality of compartments for the reception of the records each of which records is supported upon a pivoted base member which normally inclines toward the rear of the cabinet but upon depression of the forward end such member is raised at its rear end and thus operates to cause the record to roll out through the front of its compartment until brought to rest by a limiting stop. The base members are mounted upon a common pivot pin so as to be separately operable the members engaging the pin either through the medium of slots or plain holes.

One means heretofore proposed for preventing the record from rolling completely out of its compartment consists in upwardly curving the front portions of the pivoted base members.

According to the present invention the pivoted bases are straight and pivoted near their forward ends whereby the normal tendency is to remain in a position in which the forward end is at a higher elevation than the rear end with the result that in the event of a record not being required the same will always roll back to its normal position in the cabinet when the pressure of the hand on the forward end of the base has been removed. Further, the stop or stops for preventing the record from rolling completely out of the cabinet are so disposed that when a record is in abutting engagement therewith the center of the record is always behind the pivotal axis of the base member.

In order that the invention may be clearly understood the same will now be described by aid of the accompanying drawings in which:—

Figure 1 is a side elevation partly in section of a disk-record cabinet constructed in

accordance with my invention and showing the normal position of the record contained therein;

Fig. 2, a similar view showing the base depressed with the record in a position ready for removal; and

Fig. 3 a detail of one of the depressible bases.

In the drawings the bases *a* are grooved as *a'* and are pivoted near their forward ends as at *c* and the extended portion of the pivoted bases may conveniently be used for the reception of descriptive matter for the purpose of classifying the contained records. 70

A stop *m* is disposed in advance of the front of the cabinet so as to prevent the records from rolling out too far. Such stops may be constituted by a member carried by projecting arms secured to the front face of 75 the cabinet frame as will be understood.

As a means of pivotally connecting the bases to the frame the point of connection therebetween may consist of a slot *j* formed in each base (see Fig. 3) whereby the same 80 may be engaged or disengaged with or from the pivot rod without removing such rod.

As illustrated in Figs. 1 and 2 I provide stops *l* disposed one above the other to limit pivotal movement of the bases and if desired and as shown the back of each cabinet may be faced with felt or other soft material as denoted at *o* to prevent the records from becoming injured when carelessly inserted. 85

The above mentioned stops for preventing 90 the records from rolling completely out of the cabinets are so disposed that when a record is in abutting engagement therewith the center of the record is always behind the pivotal axis of the base members. 95

Having now particularly described and ascertained the nature of my said invention and in what manner the same is to be performed I declare that what I claim is:—

In a phonograph record cabinet the combination of an open sided case, a vertical partition forming within said case a compartment, a pivoted lever constituting the base of said compartment, said lever being connected to the front side of said case by a 100 pivot pin, said pivoted connection being near the forward end of the lever so that the axis of a record supported thereon is always situated behind the pivot of the lever so as to cause the record to automatically roll back 105 into the interior of the cabinet except when downward pressure is applied to the forward 110

end of the lever, the upper face of said lever having formed therein a longitudinal groove for the reception of the edge of the record, a facing of soft material on the inside face 5 of the rear side of the casing, limiting stops secured to said rear side of the casing adapted to be engaged by the rear end of said pivoted lever in its two extreme positions so as to limit the extent of the pivotal movement of the same, and an inclined stop dis-

posed across the open side of the compartment to prevent the records from rolling completely out when their respective pivoted levers are depressed.

In witness whereof I have signed this 15 specification in the presence of two witnesses.

G. WATKIN WILLIAMS.
